UNITED STATES PATENT OFFICE

134,289

DESIGN FOR A MOTOR DRIVEN REDUCTION GEAR UNIT

Gary G. Bluemink, Racine, Wis., assignor to The
Dumore Company, a corporation of Wisconsin

Application August 7, 1942, Serial No. 107,839

Term of patent 14 years

To all whom it may concern:

Be it known that I, Gary G. Bluemink, a citizen of the United States, residing at Racine, in the county of Racine and State of Wisconsin, have invented a new, original, and ornamental Design for a Motor Driven Reduction Gear Unit, of which the following is a specification, reference being had to the accompanying drawing, forming part thereof, in which—

Fig. 1 is a side elevational view of a motor driven reduction gear unit showing my new design;

Fig. 2 is an end view thereof; and

Fig. 3 is a perspective view thereof.

I claim:

The ornamental design for a motor driven reduction gear unit, as shown.

GARY G. BLUEMINK,
